UNITED STATES PATENT OFFICE.

ELMER B. GRUSH, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-BREASTING MACHINE.

Application filed July 1, 1918, Serial No. 242,764. Renewed December 28, 1922.

To all whom it may concern:

Be it known that I, ELMER B. GRUSH, a citizen of the United States, residing at Beverly, in the county of Essex and State of Massachusetts, have invented certain Improvements in Heel-Breasting Machines, of which the following description, in connection with the accompanying drawings, is a specification, like reference characters on the drawings indicating like parts in the several figures.

This invention relates to machines for operating upon heels, particularly Louis heels, and is herein shown and described as embodied in a machine for forming the breast faces of Louis heels.

The formation of a modern Louis heel, as usually performed by prior machines, involves generally three operations, viz., first the shaping of the heel longitudinally, that is, lengthwise of the shoe, in the form of a curve, this curve being concave relatively to the heel and varying in curvature from substantially nothing at the tread face to a curve of short radius adjacent to the shank of the shoe; second, the shaping of the base or seat portion of the heel breast which extends along the shoe shank, to the transverse convex curvature of the shank of the sole at this point; and third, the forming of the portion of the breast face adjacent to the tread face of the heel with a transverse concavity or scallop, this concavity being formed in that portion of the breast next to the tread face including the portion which has little or no longitudinal curvature. It is further desirable that the intermediate portion of the breast between the shank portion and the scalloped portion be concaved laterally of the heel. The surfaces or portions of the breast surface above-mentioned preferably are caused to merge into each other to form a breast of compound curvature without sharp lines of demarcation between the portions of different curvature and particularly between the scalloped portion and the intermediate portion.

An object of this invention is to provide a machine by which the breast face of a Louis heel may be completely formed with portions of different curvature and by which the various portions of different curvature may be caused to merge into each other

without lines of demarcation appearing between them.

A further object of the invention is to provide mechanism for holding a heel, and preferably a shoe with a heel attached thereto, in predetermined relation to a cutter of suitable shape and to provide such relative movement between the heel and the cutter that the various surfaces above mentioned may be formed upon the heel by operation upon the heel of the same cutter and while the heel or shoe is held in clamped position. The organization of the machine preferably includes a novel rotary cutter of the type which, when in rotation, traces a body which in longitudinal cross section has a curve corresponding substantially to the longitudinal curve of a Louis heel. In accordance with this invention, the curve of the cutter which varies in transverse section has portions corresponding in curvature to the transverse curve or concavity usually formed in the breast face of a Louis heel adjacent to the tread face thereof. As shown, the cutter is substantially egg-shaped or pear-shaped with reference to the shape traced by its cutting edges when in rotation, and is designed to effect cutting operations upon the work when the work is presented to its larger end which may be substantially hemispherical in shape and also when presented to its side portions. A cutter of this shape is not claimed herein but is disclosed and claimed in a copending application, Serial 241,393 filed June 22, 1918 by H. M. Loomer. The illustrated cutter, however, comprises a plurality of blades which are secured to the faces of a pyramidal core or carrier and the carrier is held to the cutter shaft by means of an expanding mandrel.

Very important features of the invention consist in an organization comprising means for holding a heel or a shoe with the heel attached and a cutter which may be of the form above described mounted for rotation about an axis substantially perpendicular to the tread face of the heel together with means for moving relatively the shoe holder and the cutter to effect the desired formation of each of the above described portions of the breast surface.

One such feature of the invention consists in means for effecting a lateral movement of

the cutter relatively to the heel whereby the heel is trimmed to a longitudinal curve corresponding to the curve of the cutter on a section taken in the direction of its axis. 5 Preferably the cutter is moved bodily about an axis of relatively large radius which, however, gives a substantial transverse concavity to the heel breast. This axis may, as herein shown, be located below the heel and 10 in a direction substantially parallel with the portion of the shoe sole between the shank and the ball of the shoe.

Another of these features of the invention consists in means for automatically effecting relative movement between the cutter and the shoe support or holder to cause the cutter to traverse the heel breast. The arrangement is such that the relative transverse movement may be varied and preferably is progressively variable at the will of the operator. In the organization herein shown, the cutter is swung repeatedly and automatically to and fro across the heel breast and manually operated means is provided for controlling the extent of the swinging movement of the cutter and to cause such movement to diminish or to cease when desired.

Still another such feature of the invention 30 consists in an organization by which movement of the cutter is effected to cause the cutter to trim the heel at the base of the heel to the transverse convex curve of the shank of the shoe. As herein shown, the cutter is mounted for movement about an axis extending transversely of the shoe, and means is provided for controlling movement of the cutter about this axis in the direction of the height of the heel to cause the cutter 35 to follow the convex curvature of the shank and to trim the base of the heel on a curve merging into the curve of the shank over which the base of the heel extends and into the curve of the breast above the shank portion when the cutter is moved to cause lateral transverse movement of the heel and cutter, as above described. As herein shown, 40 a changeable cam is provided to control movement of the cutter perpendicularly to the shank, which cam has a curvature corresponding to the curve of the shank of the shoe being treated.

A further feature contributing to the formation of the heel breast consists in an organization for causing relative movement of the heel and cutter in the direction of the height of the heel to effect concaving or scalloping of the portion of the breast next to the tread face of the heel. As herein shown, 55 the shoe is held in fixed position and means is provided for moving the cutter vertically of the heel and substantially in the direction of the axis of the cutter to effect the scalloping operation.

60 65 In accordance with one of the objects of

the invention, the means for controlling the automatically effective transverse movement of the cutter is correlated with the means for effecting movement of the cutter in the direction of its axis so that the transverse movements are caused gradually to cease in conjunction with the movement of the cutter in the direction of its axis to effect the scalloping operation. By this organization all sharp lines of demarcation between the 70 surface formed by the transverse movement of the cutter and the surface formed in the portion of the heel breast near the top lift by the movement of the cutter in the direction of its axis are eliminated and by the time the 75 cutter has moved in the direction of its axis sufficiently to bring the portion of the cutter having the largest radius of curvature opposite the edge of the top lift, the transverse movements of the cutter have entirely 80 ceased and the concavity in the breast face next to the top lift is formed solely by movement of the rotating cutter in the direction of its axis and of a curvature corresponding to the largest radius of the cutter. 85 90

Another feature of the invention consists in an organization including a rotary cutter constructed and arranged to be moved bodily transversely of the heel while in rotation and a shoe support adapted to hold a shoe in clamped position and arranged for movement toward and from the cutter. As shown herein, the cutter is arranged for bodily movement about an axis which is parallel to the direction of movement of the shoe support toward and from the cutter. This organization enables the support to be advanced gradually toward the cutter while the heel is treated by repeated transverse movement of the cutter.

100 105 A further feature of the invention consists in an organization including means for clamping a shoe and a cutter having an end cutting portion of curved contour arranged for rotation about an axis substantially perpendicular to the top lift of the clamped shoe and a mounting for the shoe holding means which permits movement of the shoe about a center located substantially at the center of curved contour of the cutter. Preferably adjustable means is provided to limit movement of the clamping means about said center.

110 115 An additional feature of the invention consists in an organization including shoe holding means and an egg or pear-shaped rotary cutter mounted for rotation about an axis substantially perpendicular to the tread face of a shoe in the holding means with manual means for moving the shoe holder toward the cutter in a direction substantially parallel with the shank portion of the shoe between the heel and ball, the shoe holder being also mounted for rotation about a center located substantially at the center of cur- 120 125 130

vature of the end of the pear-shaped cutter. By this organization the shoe holder may be moved about the last mentioned axis to cause the portions of the cutter of less curvature to treat a portion of the heel breast adjacent to its top lift and form thereon a concavity without effecting the treatment of other portions of the heel breast by the cutter.

These and other features of the invention will appear more fully from the following detailed description when read in connection with the accompanying drawings and will be pointed out in the appended claims. In the drawings,—

Fig. 1 is a side view of the machine partly in longitudinal section;

Fig. 2 is a perspective view of mechanism shown partly in section in Fig. 1;

Fig. 3 is a transverse sectional view of mechanism shown in Figs. 1 and 2;

Fig. 4 is a detailed view partly in section of the shoe support or holder shown in Fig. 1;

Fig. 5 is a side view of the cutter and its shaft detached from the machine; and

Fig. 6 is a sectional view on the line 6—6 of Fig. 5.

Referring to Fig. 1 of the drawings, the numeral 2 indicates the frame of the machine head which is preferably mounted on a column 4. Running longitudinally through the frame 2 from front to rear is a rock shaft 6. Outside the shaft 6 is a stationary hollow member or sleeve 8 which is mounted at its ends in openings in parts 10, 12 of the frame 2. At the ends of the sleeve 8, between it and the shaft 6, are bushings 14, 16 forming bearings for the shaft 6. Outside the member 8 is a sleeve 18 on one end of which is an eccentric 20 carrying an eccentric strap 22 for a purpose to be described, and at the other end of which a gear 24 is secured by a set screw. Outside the sleeve 18 is a sleeve 28 on one end of which is a driving pulley 30 and on the opposite end of which is a pinion 32 keyed to the sleeve 28 at 34. The pinion 32 meshes with a large gear 36 having fixed thereto a pinion 38, both gear 36 and pinion 38 being mounted on a stud shaft 40. The pinion 38 meshes with the gear 24 on the sleeve 18 carrying the eccentric 20. This construction affords a speed reduction between the pulley 30 and the eccentric 20. A loose pulley 42 having a bushing 43 is mounted loosely on the sleeve 28 between the pulley 30 and the pinion 32. Formed integrally with the driving pulley 30 is a large pulley 44 from which power is transmitted by a belt 46 to a pulley 48 fast on a hollow spindle 50. The belt 46 extends over two idlers 52 which are loosely mounted on a shaft 54 in a member 56 which has a bushed bearing 58 for the spindle 50.

The member 56 is bifurcated to receive the sleeve member 8 and a member 60 bushed at

61 on the sleeve member 8 to which member 60 the member 56 is pivoted at 62 in line with the center of the shaft 6. This construction is best shown in Fig. 2. Downward movement of the spindle carrying end 70 of the member 56 is limited by a projection 57 which contacts with a portion 63 of the member 60 and is normally maintained in contact by a spring 64 mounted between an upward projection 65 of the member 60 and the member 56 (Fig. 1). It will be seen that the member 56 is capable of two movements, one about the pivot 62 whereby the spindle 50 is moved in a vertical plane extending lengthwise of the machine and substantially perpendicular to the tread face of the heel and to the shank and the other about the center of the shaft 6 as an axis whereby the spindle 50 is moved transversely of the machine and the shoe and further that these movements may be effected without disturbing the operative relation of the pulley 48 to the pulley 44 through the belt 46, the spindle 50 being continuously driven notwithstanding these movements.

The movement of the member 56 about the pivot 62 is controlled from a treadle 70 held raised by a spring 72 and having at the rear of its pivot 74 a rod 76 connecting to an arm 78 fixed on the rear end of the shaft 6. The forward end of the shaft 6 carries an arm 79 having a flange 80 which is adapted to engage a roll 82 on the member 56. Movement of the member 56 is limited by contact of a stop 84 with the projection 65 of the member 60. The stop comprises a rod 84 threaded through a portion of the member 56 and provided with a thumb head 86 by which it may be turned.

The movement of the member 56 about the axis of the shaft 6 is effected by mechanism already partly described. The eccentric 20 has its strap 22 connected, as shown in Fig. 2, to the lower end of a grooved link member 90. The upper end of the link 90 is pivoted at 92 to a projecting arm 94 from the stationary sleeve member 8. The link 90, therefore, will have its lower end swung to and fro at a slow rate by the eccentric 20 while its upper end is stationary. Lying in the groove of the link 90 is a roll 100 mounted on one side of a curved link 102, Fig. 3. Opposite the roll 100 is another roll 104 which engages a groove in the rearwardly bent end of the arm 79. This groove is curved from the pivot 92 of the link 90 as a center. Obviously, when the shaft 6, to which the arm 7, is fixed, is rocked by the treadle the roll 100 will be moved up and down in the groove of the link 90 and consequently more or less movement will be communicated to the link 102. The link 102 has its opposite end pivoted at 103 to a curved lever 106 fulcrumed at 108 to a lug 109 on the arm 94 of the stationary

- sleeve member 8. The lower end of the lever 106 is forked to embrace a roll 110 on the downwardly projecting end 63 of the member 60. Oscillation of the link 90 communicated through the link 102 to the lever 106 will, therefore, cause the member 60 to be rocked about the axis of the shaft 6 and with it, of course, will move the member 56 and the spindle 50.
- 10 The spindle 50 is hollow and through it extends a rod 120 which has a head 124 pinned to its upper end by which it may be turned. The lower end of the rod 120 is threaded into a tapered nut 121 which engages a similar formation in the end of the spindle 50 which is split at 51 to permit expansion of it by the nut 121. The end of the spindle 50 is adapted to enter when contracted a hole 53 in the body portion 123 of 15 the cutter designated in general by the numeral 122. The portion 123 is a square pyramid in shape, and to each of its sides is secured a cutter blade 125 by means of dowel pins 127 and a nut 129. The shape 20 and arrangement of the cutters is clearly shown in Figs. 5 and 6. By placing the cutter 122 upon the end of the spindle 50 and turning the head 124, the spindle is expanded to hold the cutter upon the spindle.
- 25 In referring to the cutter as pear-shaped, reference is made, of course, to the shape traced in space by the cutting edges when the cutter is in rotation. This shape comprises an end portion of substantially hemispherical shape and side portions of less curvature.
- 30 The work support will now be described. Extending horizontally from the machine frame are two members 130, 132 on the inner faces of which guideways 134 are 35 formed. Arranged to slide in the ways are rectangular portions 136 of a U-shaped member 137 which depends between them. Above the rectangular portions 136 are ears 138 to each of which is pivoted at 139 a part 140, the parts 140 being connected by a plate 142 extending between them and against which the tread face of the heel of a shoe is presented. To position the heel 40 longitudinally, a plate 144 is provided which has a V-shaped notch to receive the rear end of the heel and is adjustably held to the plate 142 by a thumb screw 146. To clamp the shoe against the plate 142 a U-shaped 45 member 150 is provided which embraces the shoe and has its ends pivoted to the parts 140 at 141. Movement of the member 150 about the pivots 141 is limited in one direction by the plate 142 (see dotted lines Fig. 4) and in the other by lugs 152 on the members 140. In the bight of the U-shaped member 150 is a recess containing a nut 154 having an operating handle 155 and threaded by coarse threads to a sleeve 156 50 which passes freely through the member

150. Extending through the sleeve 156 is a rod 160 having a head 162 at one end to engage the last and at the other a knob 164 by which the head 162 is pushed into engagement with the last. A pawl 166 is pivoted 70 between ears 168 on the sleeve 156 and is normally held by a leaf spring 169 (Fig. 1) in engagement with teeth 170 on the rod 160, the teeth being arranged to prevent movement of the rod away from the last. The pawl 166 has a thumb piece 167 by which it may be readily released. After the rod 160 has been pushed against the last and is held in that position by the pawl 166, the nut 154 is operated by the handle 155 to move the sleeve 156 toward the last and therefore cause the pawl to move the rod 160 further forcibly to press the head 162 against the last to clamp the tread of the heel against the plate 142. Outside the nut 154 a cap piece 174 is secured at 175 to the member 150. This forms an abutment for the nut 154 and has a slot 176 to receive the ears 168 to which the pawl 166 is pivoted and prevent rotation of the sleeve 156. The spring 169 is conveniently anchored to the cap piece 174, the relative movement between this and the pawl release 167 being insufficient to disturb the operative relation of the spring. 95

After being clamped as described, the shoe and shoe holding means (142, 162) are free to move about the pivot 139 to the position shown in Fig. 1 where a lug 180 on the parts 140 comes into engagement with an adjustable stop screw 182 shown as a screw threaded through a projection 184 from the ear 138 on the member 137. On the screw 182 is a set nut having an operating handle 186 to hold the screw from rotation. Adjustment 105 of the screw 182 varies the position of the shoe about the axis of the pivot 139 which, when the shoe is in operative relation to the cutter, passes through the cutter approximately at the center of curvature of its 110 rounded end.

The shoe positioning and holding means, when positioned as described, may slide to carry the shoe toward and from the cutter in a horizontal direction on the guideways 115 134. It is important that this movement, as the shoe approaches the cutter, be under delicate and positive control by the operator. For this purpose teeth 190 are formed in the lower edge of one of the rectangular portions 136 of the member 137 which teeth are engaged by a pinion 192 on a shaft 194 journaled in the horizontally extending member 130. On the outer end of the shaft 194 is a hand wheel 196 by which the pinion 192 may be rotated to move the shoe holding means toward and from the cutter 122. 120

When the machine is in operation, it will be understood that the cutter shaft 50 will 130

be rotated at high speed from the pulley 44, that, through the reducing gearing described, the eccentric 20 will be rotated at low speed; that the eccentric strap 22 will cause the link 5 90 to swing on the center 92, and that the motion of the link 90 will be communicated through the link 102 to the lever 106 which will be swung to communicate the swinging movement to the cutter head 56 and will cause maximum swinging movement thereof laterally of the heel. The operator places a shoe having a last therein with the tread face of its heel resting against the plate 142, the longitudinal position of the heel being determined by the adjustable plate 144 which engages the rear end of the heel. He then pushes the plunger 160 against the last, where it is held by the pawl 166, and operates the handle 155 to complete the clamping of the 20 shoe. This clamping of the shoe may be done while the plate 142 is in the position shown in Fig. 4, the shoe being positioned as shown and the clamp being swung from the dotted line position to the full line position of that figure. The shoe and its clamp are then 25 swung about the center 139 into the position shown in Fig. 1 and the shoe and clamp are pushed bodily toward the cutter 122. As the shoe approaches the cutter, the pinion 30 192 engages the teeth 190 on the slide 136 and the advance of the shoe toward the cutter may then be delicately controlled by manipulating the hand wheel 196. As the cutter swings across the heel breast, the central 35 portion of the breast is trimmed to a longitudinal concave curve corresponding to the curve of the side portion of the cutter and is trimmed also to a transverse curve by reason of the movement of the cutter in a circular 40 arc about the axis of the shaft 6. At the same time the end portion of the cutter is caused to follow the convex curve of the shank by reason of its movement about the same axis 6 which lies substantially parallel 45 with the portion of the shank between the breast of the heel and the ball of the shoe. This movement, however, is modified by contact of a roll 198 on the head 56 with a cam 200 fixed to the frame 130 of the work support. The cam 200 is designed to effect a 50 slight movement of the head 56 about its transverse axis 62 to cause the lateral traverse of the end of the cutter to correspond accurately with the curve of the shank, different 55 cams being provided to take care of different styles or curvatures of the shanks. After these operations have been effected, the treadle 70 is actuated to cause swinging movement of the cutter to cease and to effect 60 movement of the cutter substantially in the direction of its axis about the center 62 to effect the scalloping operation upon the heel. This movement of the cutter in the direction of its axis while the lateral movements are 65 gradually ceasing causes the breast portion of the heel adjacent to the top lift to be given a transverse curvature or scallop corresponding to that of the cutter at its largest radius and this scalloped portion merges into the adjacent surface of the heel having a curvature of larger radius determined by the movement of the cutter about the axis 6. 70

If a scallop of smaller curvature is desired, as for instance, upon a heel having a small top lift, the heel may be moved away from 75 the cutter before the cutter is raised and the top portion of the breast again presented to a portion of the cutter nearer its end and having, therefore, a smaller radius of curvature. The stop 84 may be used to limit movement of the cutter and secure uniformity of work when the tread portion of the breast is presented for the scalloping operation, as described, to portions of the cutter below its 80 largest diameter. 85

Having thus described my invention, what I claim as new and desire to secure by Letters Patent of the United States is:

1. A machine for breasting Louis heels comprising a shoe support and a cutter constructed and arranged for relative movement to cause the cutter to curve the heel breast longitudinally and also to curve the base portion of the heel correspondingly to the transverse curve of the shoe shank and to scallop 90 the portion only of the heel breast which is adjacent to the top lift.
2. A machine for breasting Louis heels comprising a shoe support and a cutter constructed and arranged for relative movement 100 to cause the cutter to curve the heel breast longitudinally and also to curve the base portion of the heel correspondingly to the transverse curve of the shoe shank and to concave 95 the portion of the heel breast adjacent to the top lift, said relative movement differently curving the portion of the heel breast between the shank portion and the portion adjacent to the top lift. 105
3. A machine for breasting Louis heels 110 comprising a shoe support and a cutter constructed and arranged for relative movements to cause the cutter to curve the heel breast longitudinally and also to curve the base portion of the heel correspondingly to the transverse curve of the shoe shank and to concave 115 the portion of the heel breast adjacent to the top lift, and means for correlating said relative movements to cause the lines of demarcation between the breast portions of different transverse curvature to be obliterated. 120
4. A machine for breasting Louis heels comprising a shoe support and a cutter constructed and arranged for relative movement 125 to cause the cutter to curve the heel breast longitudinally and also to curve the base portion of the heel correspondingly to the transverse curve of the shoe shank and transversely to concave the portion only of 130

- the heel breast which is adjacent to the top lift, and means for effecting the formation of said transverse curvatures coincidently with the formation of the longitudinal curvature.
5. A machine for breasting Louis heels comprising a shoe support and a cutter constructed and arranged for relative movements to cause the cutter to curve the heel breast longitudinally and transversely and transversely to concave the portion of the heel breast adjacent to the top lift at a different curvature.
10. A machine for breasting Louis heels comprising a shoe support and a cutter constructed and arranged for relative movements to cause the cutter to curve the heel breast longitudinally and transversely and transversely to concave the portion of the heel breast adjacent to the top lift at a different curvature, and means for correlating said relative movements to cause the lines of demarcation between the transversely curved portions to be obliterated.
15. A machine for breasting Louis heels comprising a shoe support and a cutter constructed and arranged for relative movement to cause the cutter to curve the heel breast longitudinally and to scallop the portion of the heel breast adjacent to the top lift.
20. A machine for breasting Louis heels comprising a shoe support and a cutter constructed and arranged for relative movement to cause the cutter to curve the heel breast longitudinally and to scallop the portion of the heel breast adjacent to the top lift, and means to effect relative movement between the cutter and the heel during the scalloping operation to obliterate the lines of demarcation between the scalloped portion and the adjacent portion of the heel.
25. A machine for breasting Louis heels comprising a shoe support, a cutter having a curved cutting edge, means for moving the cutter transversely of the heel to form a longitudinal curvature on the heel breast, means to cause the cutter during its traversing movement to follow the curve of the shank, and means to cause the cutter to form a scallop on the portion of the breast face adjacent to the top lift.
30. A machine for breasting Louis heels comprising a shoe support, a cutter having a curved cutting edge, means for moving the cutter transversely of the heel to form a longitudinal curvature on the heel breast, means to cause the cutter during its traversing movement to follow the curve of the shank, means to cause the cutter to form a scallop on the portion of the breast face adjacent to the top lift, and means for effecting correlation of the cutter movements to cause the differently curved por-
- tions of the breast face to merge into each other without lines of demarcation occurring between them.
35. A machine for breasting Louis heels comprising a shoe support and a cutter constructed and arranged for relative movement to cause the cutter to form the heel breast as a whole with a longitudinal curvature, the base portion of the heel to be formed with a base corresponding to the shoe shank and the portion adjacent to the top lift only to be formed with a concavity.
40. In a machine for breasting Louis heels, the combination of a pear-shaped cutter, a heel support, and means constructed and arranged for moving the cutter relatively to the support to cause the heel of a shoe on the support to be breasted with a longitudinal curvature.
45. In a machine for breasting heels, the combination of a shoe support, a pear-shaped cutter mounted on an axis substantially perpendicular to the portion of the shoe shank adjacent to the heel, and means constructed and arranged for moving the cutter relatively to the support to cause the heel of a shoe on the support to be breasted.
50. In a machine for breasting heels, the combination of a heel support, a pear-shaped rotary cutter having its axis substantially perpendicular to the plane of the tread face of the heel, and means constructed and arranged for effecting automatically relative movement between the cutter and the support to cause the heel on the support to be breasted.
55. In a machine for breasting heels, the combination of a heel support, a pear-shaped rotary cutter having its axis extending in the direction of the height of the heel, and means carrying the cutter constructed and arranged for bodily movement to cause the heel on the support to be breasted with a longitudinal curvature corresponding to the curve of the cutter in longitudinal cross section.
60. In a machine for breasting heels, the combination of a shoe support, a pear-shaped cutter mounted on an axis substantially perpendicular to the plane of the portion of the shoe shank adjacent to the heel, and power means for moving the cutter relatively to the support to cause the heel of the shoe on the support to be breasted.
65. In a machine for breasting heels, the combination of a shoe support, a pear-shaped cutter mounted on an axis perpendicular to the plane of the tread face of the heel, and means constructed and arranged for relatively moving the cutter and the support in a direction laterally of the breast to form the breast face of the heel and also perpendicularly to the shank portion of the shoe to

cause the breast portion adjacent to the shank to be trimmed to the lateral curvature of the shank.

18. A heel breasting machine having, in combination, means for supporting the tread face of the heel of a shoe, and a rotary cutter having an end cutting portion and arranged with its axis substantially in the longitudinally median plane of the shoe, said cutter being constructed and arranged for bodily movement about a center located substantially at the center of transverse curvature of the shank.

19. In a machine of the class described, the combination of a shoe support, a rotary cutter mounted on an axis extending substantially perpendicularly to the plane of the top lift, and power means for effecting relative movement of the cutter and the shoe support to cause relative traverse of the heel and cutter in a direction parallel to the shank of the shoe.

20. In a machine of the class described, the combination of a shoe support, a rotary cutter mounted upon an axis extending substantially perpendicular to the plane of the top lift of the heel of a shoe on the support, and means for effecting bodily movement of the cutter transversely of the heel about an axis approximately parallel with the shank.

21. In a machine for breasting heels, the combination of a heel support, a pear-shaped rotary cutter having its axis substantially perpendicular to the plane of the tread face of the heel, and means constructed and arranged for effecting automatically repeated relative movement between the cutter and the support to cause the heel on the support to be breasted progressively.

22. In a machine for breasting heels, the combination of a heel support, a pear-shaped cutter mounted on an axis extending in the direction of the height of a heel on the support, and means constructed and arranged for effecting automatically relative movement of the cutter and the support to cause the heel on the support to be breasted in a curve corresponding to the longitudinal curvature of the cutter.

23. A machine of the class described having, in combination, means for supporting the tread face of the heel of a shoe, a rotary cutter having an end cutting portion and a side cutting portion arranged with its end cutting portion directed toward the shank of the shoe and its side cutting portion directed toward the breast of the heel, and automatic means for effecting repeated traverse of the heel breast by the cutter during the breasting operation.

24. In a machine of the class described, the combination of a shoe support, a rotary cutter mounted on an axis extending substantially perpendicularly to the plane of

the top lift of a shoe on the support, and power means for effecting repeated bodily swinging movement of the cutter transversely of the heel.

25. In a machine for breasting Louis heels, the combination of a rotary cutter presented end on to a shoe shank, said cutter having cutting edges contoured to trim the breast and base portion of the heel, a shoe support, and means for moving the cutter bodily about a center so located as to cause the heel breast to be trimmed from side to side and the base portion to be trimmed to the curvature of the shank.

26. In a machine of the class described, the combination of a shoe support, a rotary cutter mounted on an axis extending substantially perpendicularly to the plane of the top lift of the heel of a shoe on the support and arranged to form the surface of the breast of the heel, and means for effecting bodily swinging movement of the cutter transversely of the heel from side to side of the heel.

27. In a machine of the class described, the combination of a shoe support, a rotary cutter mounted on an axis extending substantially perpendicularly to the plane of the top lift of a shoe on the support, means for effecting bodily swinging movement of the cutter transversely of the heel, and means for varying the extent of said bodily swinging movement.

28. In a machine for breasting heels, the combination of a heel support, a pear-shaped cutter mounted on an axis extending in the direction of the height of a heel on the support, means constructed and arranged for effecting automatically relative movement of the cutter and the support to cause the heel on the support to be breasted in a curve corresponding to the longitudinal curvature of the cutter, and means for controlling the extent of said automatic movement.

29. In a machine for breasting heels, the combination of a heel support, a pear-shaped rotary cutter having its axis substantially perpendicular to the plane of the tread face of the heel, means constructed and arranged for effecting automatically relative movement between the cutter and the support to cause the heel on the support to be breasted, and manually controlled means for varying the extent of automatically effected relative movement between the cutter and the support.

30. In a machine of the class described, the combination of a shoe support, a rotary cutter mounted on an axis extending substantially perpendicularly to the plane of the top lift of a shoe on the support, means for effecting bodily movement of the cutter transversely of the heel about a center approximately parallel with the inclined portion of the shank lying between the heel and the

- ball of the shoe, and manual means for controlling the movements of the cutter.
31. In a machine of the class described, the combination of a shoe support, a rotary cutter mounted on an axis extending substantially perpendicular to the plane of the top lift and arranged to operate on the breast of the shoe heel in a direction from side to side of the heel, and power means for relatively moving the cutter and the shoe support to cause the cutter to traverse the heel breast. 70
32. In a machine of the class described, the combination of a shoe support, a rotary cutter mounted on an axis extending substantially perpendicular to the plane of the top lift, power means for relatively moving the cutter and the shoe support to cause the cutter to traverse the heel, and means for varying said relative movement. 80
33. In a machine of the class described, the combination of a shoe support, a rotary cutter mounted on an axis extending substantially perpendicular to the plane of the top lift, power means for relatively moving the cutter and the shoe support to cause the cutter to traverse the heel, and means for progressively varying said relative movement. 85
34. In a machine of the class described, the combination of a shoe support, a rotary cutter mounted on an axis extending substantially perpendicular to the plane of the top lift, power means for relatively moving the cutter and the shoe support to cause the cutter to traverse the heel, and means for varying at will said relative movement. 95
35. In a machine of the class described, the combination of a shoe support, a rotary cutter mounted on an axis extending substantially perpendicularly to the plane of the top lift, power means for effecting movement of the cutter relative to the shoe support to cause relative traverse of the heel and cutter in a direction parallel to the shank of the shoe, and means for varying the extent of said relative movement. 100
36. In a machine of the class described, the combination of a shoe support, a rotary cutter mounted on an axis extending substantially perpendicularly to the plane of the top lift, power means for effecting movements of the cutter relative to the shoe support to cause the cutter to traverse the heel in a direction parallel to the shank of the shoe, and means for progressively varying the extent of said movements of the cutter. 115
37. In a machine of the class described, the combination of a shoe support, a rotary cutter mounted on an axis extending substantially perpendicularly to the plane of the top lift, power means for effecting movements of the cutter relative to the shoe support to cause the cutter to traverse the heel in a direction parallel to the shank of the shoe. 120
38. In a machine of the class described, the combination of a shoe support, a rotary cutter mounted on an axis extending substantially perpendicularly to the plane of the top lift of a shoe on the support, means for effecting bodily swinging movement of the cutter transversely of the heel, and means for varying at will the extent of said bodily swinging movement. 125
39. In a machine for breasting heels, the combination of a shoe support, a pear-shaped rotary cutter having its axis substantially perpendicular to the plane of the tread face of the heel of a shoe on said support, power means constructed and arranged for effecting relative movement of the cutter and the support to cause the heel of the shoe to be breasted, and manually controlled means for varying the extent of said power effected movement. 130
40. In a machine for breasting heels, the combination of a shoe support, a pear-shaped cutter mounted on an axis perpendicular to the plane of the tread face of the heel, means constructed and arranged for relatively moving the cutter and the support in a direction laterally of the breast to form the breast face of the heel and also perpendicular to the shank portion of the shoe to cause the breast portion adjacent to the shank to be trimmed to the lateral curvature of the shank, and means for increasing the perpendicular movement and simultaneously causing the lateral movement to cease to cause the portion of the breast near the tread face to be concaved. 140
41. A machine of the class described having, in combination, means for supporting the tread face of the heel of a shoe, a rotary cutter having an end cutting portion and a side cutting portion arranged with its end cutting portion directed toward the shank of the shoe and its side cutting portion directed toward the breast of the heel, and automatic means constructed and arranged for effecting relative movement of the shoe and cutter to cause the end cutting portion of the cutter to follow the transverse curve of the shank and the side cutting portion to traverse the heel breast from side to side. 150
42. In a machine for breasting heels, the combination of a pear-shaped cutter, a heel support, and means constructed and arranged for relatively moving the cutter and the support in a direction laterally of the breast to form the breast face of the heel, said cutter being movable in the direction of its axis to cause the breast portion adjacent to the shank to be trimmed to the lateral curvature of the shank. 160
43. In a machine of the class described, the combination of a shoe support, a rotary cutter mounted upon an axis extending sub-

stantially perpendicular to the plane of the top lift, and means for moving the cutter relatively to the shoe support to cause the cutter to traverse the heel from side to side of the heel in a direction parallel to the shank of the shoe and in contact with the heel breast.

44. In a machine of the class described, the combination of a shoe support, a rotary cutter mounted upon an axis extending substantially perpendicular to the plane of the top lift of the heel of a shoe on the support, and means for effecting bodily movement of the cutter transversely of the heel about 5 a center approximately at the center of curvature of the shank.

45. In a machine for breasting heels, the combination of a shoe support, a pear-shaped cutter mounted on an axis substantially perpendicular to the portion of the shoe shank adjacent to the heel, and means constructed and arranged for moving the cutter relatively to the support to cause the heel of the shoe on the support 20 to be breasted and to maintain the direction of said axis perpendicular to the curve of the shank during the said relative movement.

46. In a machine for breasting heels, the combination of a heel support, a pear-shaped rotary cutter having an axis perpendicular to the plane of the tread face of a heel on the support, and means constructed and arranged for moving the cutter relatively to the support in a direction lateral of the heel and for causing the cutter to follow the transverse curvature of the heel seat face of the heel during its lateral movement.

47. In a machine of the class described, the combination of a shoe support, a rotary cutter mounted on an axis extending substantially perpendicularly to the plane of the top lift, power means for effecting relative movement of the cutter and the shoe support to cause relative traverse of the heel and cutter in a direction parallel to the shank of the shoe, and means for progressively varying the extent of said relative movement.

48. In a machine of the class described, the combination of a shoe support, a rotary cutter mounted on an axis extending substantially perpendicularly to the plane of the top lift, power means for effecting relative movement of the cutter and the shoe support to cause the cutter to traverse the heel in a direction parallel to the shank of the shoe, and means for varying at will the extent of said relative movement.

49. In a machine of the class described, the combination of a shoe support, a rotary cutter mounted on an axis extending substantially perpendicularly to the plane of the top lift of the shoe on the support, and

means for effecting bodily movement of the cutter transversely of the heel about a center approximately parallel to the inclined portion of the shank lying between the heel and the ball of the shoe.

70

50. A machine of the class described having, in combination, a support for the tread face of the heel of a shoe, a rotary cutter having an end cutting portion and arranged with its end face directed toward the shank 75 of the shoe, said support and cutter being constructed and arranged for relative movement about an axis extending longitudinally of the shoe to cause the cutter to trim the heel from side to side of the heel, and additional means to cause the cutter to follow the curve of the shank during said relative movement.

51. A machine of the class described having, in combination, a support for the tread 80 face of the heel of a shoe, a rotary cutter having an end cutting portion and arranged with its end face directed toward the shank of the shoe, said support and cutter being constructed and arranged for relative movement about an axis extending longitudinally 85 of the shoe to cause the cutter to trim the heel from side to side of the heel, and a changeable cam for causing the cutter to follow the curve of the shank during said 90 relative movement.

52. A heel breasting machine having, in combination, means for supporting the tread face of the heel of a shoe, and a rotary cutter having an end cutting portion arranged with its axis in the longitudinal median plane of the shoe and its end portion directed toward the shoe shank, said cutter being constructed and arranged for movement substantially in the direction of 105 its axis to cause the end of the cutter to follow the transverse curvature of the shank of the shoe.

53. In a machine of the class described, the combination of a heel support, a rotary 110 cutter having a diameter less than the largest dimension of the heel and having its axis substantially perpendicular to the plane of the tread face of the heel, and a changeable cam for relatively moving the 115 cutter and the heel in the direction of the height of the heel to cause the cutter to follow the convex surface on the shoe shank.

54. In a machine of the class described, the combination of a rotary cutter having 120 end portions substantially hemispherical in shape, a shoe support arranged for movement about a center located substantially at the center of curvature of said hemispherical portion of the cutter, and means for 125 relatively moving the shoe support and cutter in the direction of the shoe shank longitudinally of the shoe.

55. In a machine for breasting heels, the combination of a shoe support, a pear- 130

shaped rotary cutter having its axis substantially perpendicular to the plane of the tread face of the heel of the shoe on the support, means acting automatically to move the cutter and the support relatively to cause the cutter to breast the heel in a direction transversely of the heel breast, and means for causing the automatically effected movements to cease and to relatively move the shoe support and cutter in the direction of the height of the heel.

56. In a machine for breasting heels, the combination of a shoe support, a pear-shaped rotary cutter having its axis substantially perpendicular to the plane of the tread face of the heel, means for causing relative movement between the cutter and the shoe support to cause the breast face of the heel to be formed from side to side of the heel, and means for effecting relative movement between the support and the cutter in the direction of the axis of the cutter to cause the cutter to form a concave surface in the heel breast adjacent to the top lift.

57. In a machine of the class described, the combination of a heel support, a rotary cutter having a diameter less than the largest dimension of the heel and having its axis substantially perpendicular to the plane of the tread face of the heel, and means for relatively moving the cutter and the heel in the direction of the height of the heel to cause the cutter to form a concave surface in the heel breast.

58. In a machine for breasting heels, the combination of a shoe support, a pear-shaped rotary cutter having its axis substantially perpendicular to the plane of the tread face of the heel, means for effecting movement of the cutter to cause the breast face of the heel to be formed laterally of the heel, and means for effecting movement of the cutter in the direction of its axis to cause the cutter to form a concave surface in the heel breast adjacent to the top lift.

59. In a machine for breasting heels, the combination of a shoe support, a pear-shaped rotary cutter having its axis substantially perpendicular to the plane of the tread face of the heel of a shoe on the support, means acting automatically to move the cutter relatively to the support to cause the cutter to breast the heel in a direction transversely of the heel breast, and means for causing the automatically effected movements to cease and for moving the cutter in the direction of the height of the heel to cause the cutter to form a concave face in the portion of the breast adjacent to the top lift.

60. A heel breasting machine having, in combination, shoe positioning means, a rotary cutter having its axis directed end

on to the shank of the shoe, automatic means for moving relatively said positioning means and cutter to cause the cutter to traverse the heel breast, said cutter being movable longitudinally of the heel, and means for effecting said longitudinal movement during said traversing movement of the cutter.

61. In a machine for breasting heels, the combination of a heel support, a pear-shaped rotary cutter mounted on an axis substantially perpendicular to the plane of the tread face of a heel on the support, means constructed and arranged for automatically moving the cutter and the support relatively laterally of the breast to form the breast face of the heel and also in the direction of its axis to cause the breast portion adjacent to the shank to be trimmed to the lateral curvature of the shank, means for effecting further movement of the cutter to effect scalloping of the heel, and means for causing the lateral movement gradually to cease as the scalloping operation proceeds to cause lines of demarcation between the breast face and the scalloped portion to be eradicated.

62. In a machine for breasting heels, the combination of a heel support, a pear-shaped rotary cutter having its axis substantially perpendicular to the plane of the tread face of the heel, means constructed and arranged for effecting automatically repeated relative movement between the cutter and the support to cause the heel on the support to be breasted, and manually controlled means for feeding the shoe during the automatically repeated relative movement between the cutter and the support.

63. A machine of the class described having, in combination, means for supporting the tread face of the heel of a shoe, a rotary cutter having an end cutting portion and a side cutting portion arranged with its end cutting portion directed toward the shank of the shoe and its side cutting portion directed toward the breast of the heel, automatic means for effecting repeated traverse of the heel breast by the cutter during the breasting operation, and means for relatively moving the heel and cutter to feed the heel gradually toward the cutter for removal of the material from the breast by successive traverses of the cutter.

64. In a machine of the class described, the combination of a pear-shaped rotary cutter mounted for rotation about its longitudinal axis, a shoe support constructed and arranged to present a heel to the cutter with the plane of the tread face of the heel perpendicular to the axis of the cutter, means for moving the support toward the cutter in a direction substantially parallel with the inclined portion of the shoe shank lying between the heel and the ball, and means for

moving the cutter transversely of the shoe about an axis located parallel with said shank portion.

65. In a machine of the class described, 5 the combination of a pear-shaped rotary cutter mounted for rotation about its longitudinal axis, a shoe support constructed and arranged to present a heel to the cutter with the plane of the tread face of the heel perpendicular to the axis of the cutter, means for moving the support toward the cutter in a direction substantially parallel with the inclined portion of the shoe shank lying between the heel and the ball, and power 10 means for effecting repeated movement of the knife transversely of the shoe about an axis located parallel with said shank portion.

66. In a machine of the class described, 20 the combination of a pear-shaped rotary cutter mounted for rotation about its longitudinal axis, a shoe support constructed and arranged to present a heel to the cutter with the plane of the tread face of the heel perpendicular to the axis of the cutter, means for moving the support toward the cutter in a direction substantially parallel with the inclined portion of the shoe shank lying between the heel and the ball, and means for 25 moving the cutter and the support relatively about a center located at approximately the center of curvature of the end of the cutter.

67. In a machine of the class described, 35 the combination of a pear-shaped rotary cutter mounted for rotation about its longitudinal axis, a shoe support constructed and arranged to present a heel to the cutter with the plane of the tread face of the heel perpendicular to the axis of the cutter, and means for moving the support toward the cutter in a direction substantially parallel with a portion of the shoe shank lying between the heel and the ball.

68. In a machine of the class described, 45 the combination of a rotary cutter having an end portion substantially hemispherical in shape, and a shoe support arranged for movement about a center located substantially at the center of curvature of said hemispherical portion of the cutter.

69. In a machine of the class described, 55 the combination of a pear-shaped rotary cutter mounted for rotation about its longitudinal axis, a shoe support constructed and arranged to present a heel to the cutter with the plane of the tread face of the heel perpendicular to the axis of the cutter, and means for moving the support toward the cutter in a direction substantially parallel with the portion of the shoe shank lying between the heel and the ball to cause the cutter to act on the breast and base portion of the heel and to approach the portion of the shank which is parallel with the plane 60 of the top lift.

70. A machine of the class described having, in combination, a rotary cutter constructed and arranged for presentation end on to the bottom of a shoe, means for positioning the shoe for the action of the cutter, 70 means for measuring the height of the shoe and last, and means including a screw for effecting powerful pressure through the measuring means against the last to hold the last against the shoe positioning means. 75

71. A machine of the class described having, in combination, a rotary cutter constructed and arranged for presentation end on to the bottom of a shoe, means for positioning the shoe for the action of the cutter, means for measuring the height of the shoe and last, and means comprising a screw and a nut having a lever for applying pressure to the last through the measuring means to hold the shoe clamped against the 80 shoe positioning means.

72. A heel breasting cutter comprising a pyramidal core and a blade secured to each face of the core, the edges of the blades being arranged to meet at one end in the axis of 90 the cutter and formed to trace a pear-shaped body when in rotation.

73. A heel breasting machine having, in combination, means for supporting the tread face of the heel of a shoe, a rotary 95 cutter having an end cutting portion and arranged with its axis extending radially of the curve of the shank, and means constructed and arranged for relatively moving the cutter and the support in a direction laterally of the heel to form the breast face of the heel and also perpendicularly to the shank portion of the shoe to cause the breast portion adjacent to the shank to be trimmed to the lateral curvature of the shank. 100

74. In a machine of the class described, the combination of a shoe support, a rotary cutter mounted on an axis extending substantially perpendicular to the plane of the top lift of a shoe on the support, and means 110 for effecting bodily swinging movement of the cutter transversely of the heel to cause the cutter to form the breast face of the heel.

75. In a machine for operating upon the 115 heels of boots and shoes, the combination of a rotary cutter, a shoe carrier, and means for moving relatively the cutter and carrier first to effect treatment of the whole heel breast by the cutter and then to effect a second operation of the cutter upon a portion only of the heel breast. 120

76. A machine of the class described having, in combination, means for supporting the tread face of the heel of a shoe, a rotary cutter, means for effecting repeated traverses of the heel breast and cutter during the breasting operation, and means for relatively moving the heel and cutter to feed the heel gradually toward the cutter for re- 125 130

moval of the material from the breast by successive relative traverses of the heel and cutter.

77. A machine for breasting Louis heels comprising a shoe support, and a cutter constructed and arranged for relative movement to cause the cutter to trim the base portion of the heel breast in accordance with the curve of the shank and to scallop the 10 portion of the heel breast adjacent to the top lift.

78. In a heel breasting machine, a shoe support, rotary breasting means constructed and arranged to be driven at high speed, 15 speed reducing mechanism, and connections for causing power movement of the breasting means relatively to the shoe heel to effect the breasting operation.

79. In a heel breasting machine, a shoe 20 support, rotary breasting means, a main shaft, connections from the main shaft to the rotary means, speed reducing mechanism from the main shaft, and connections from said mechanism to the breasting means to 25 effect movement of the breasting means relatively to the work support to cause the heel of the shoe to be breasted.

80. In a heel breasting machine, a shoe 30 support, rotary breasting means, a main shaft, belt means from the main shaft to the rotary means, speed reducing mechanism from the main shaft, and connections to effect bodily movement of the breasting means relatively to the shoe heel to effect the 35 breasting operation.

81. In a heel breasting machine, a shoe support, rotary breasting means, a main shaft, belt means from the main shaft to the rotary means, speed reducing mechanism 40 from the main shaft, and connections to effect movement of the breasting means to cause the base portion of the heel to be trimmed to correspond to the transverse curvature of the shank.

45 82. In a heel breasting machine, a work support, rotary heel breasting means, manually operated means for moving the support toward and from the breasting means, and power operated means for effecting repeated movements of the rotary breasting 50 means transversely of the heel breast.

83. In a machine of the class described, the combination of a rotary tool for treating a shoe, power means for operating the tool, 55 a rocking member continuously operated by power, connections from the rocking member to the tool to effect movement thereof from the rocking member, and manual means for varying the relation of the connections to the rocking member to vary the movement of the tool.

84. In a machine of the class described, the combination of a shoe support, a rotary cutter constructed and arranged to act on the 60 breast of the heel of the shoe by movement

from side to side of the heel, and power means for moving the cutter to cause the cutter to traverse the heel breast.

85. In a machine of the class described, the combination of a shoe support, a rotary cutter constructed and arranged to act on the breast of the heel of the shoe by movement from side to side of the heel, power means for moving the cutter to cause the cutter to traverse the heel breast, and means for varying 75 the extent of said traversing movement.

86. In a machine of the class described, the combination of a shoe support, a rotary cutter, power means for effecting relative movement between the cutter and the shoe support to cause the cutter to act on the heel breast, and means for varying said relative movement.

87. In a machine of the class described, the combination of a shoe support, a rotary cutter, power means for effecting relative movement between the cutter and the shoe support to cause the cutter to act on the heel breast, and means for progressively varying 85 the extent of said relative movement.

88. In a machine of the class described, the combination of a shoe support, a rotary cutter, power means for effecting relative movement between the cutter and the shoe support to cause the cutter to act on the heel breast, and means for varying at the will of 95 the operator the extent of said relative movement while the cutter is acting on the heel breast.

89. In a machine of the class described, the combination of a shoe support, a rotary cutter movable transversely and heightwise of the breast of the heel on the support, power means for effecting transverse movement of the cutter, and means for controlling the extent of said transverse movement.

90. In a machine of the class described, the combination of a shoe support, a rotary cutter movable transversely and heightwise 110 of the breast of the heel on the support, power means for effecting transverse movement of the cutter, and means for controlling the extent of said transverse movement and effecting movement of the cutter heightwise of the heel breast.

91. In a machine of the class described, the combination of a shoe support, a rotary cutter movable transversely and heightwise 115 of the breast of the heel on the support, power means for effecting transverse movement of the cutter, and a single manually controlled means for varying the extent of said transverse movement and for moving the cutter heightwise of the heel.

92. In a machine of the class described, the combination of a shoe support, a rotary cutter movable transversely and heightwise 120 of the breast of the heel on the support, power means for effecting transverse movement of the cutter, and a single manually controlled means for varying the extent of said transverse movement and for moving the cutter heightwise of the heel.

- ment of the cutter, and manually operated means acting to vary the extent of said transverse movement and to move the cutter heightwise of the heel.
93. In a machine of the class described, the combination of a shoe support, a rotary cutter movable transversely and heightwise of the breast of the heel on the support, power means for effecting transverse movement of the cutter, and manually operated means acting, upon continuous movement in a single direction, progressively to diminish the extent of said transverse movement and then to move the cutter heightwise of the heel. 70
94. In a machine of the class described, the combination of a rotary cutter arranged to act on a heel breast, and a shoe support for holding the work in operative relation to the cutter, said support being arranged for movement about an axis extending transversely of the shoe adjacent to the center of longitudinal curvature of the heel. 75
95. In a machine of the class described, the combination of a rotary cutter arranged to act on a heel breast, and a shoe support for holding the work in operative relation to the cutter, said support being arranged for movement about an axis extending transversely of the shoe above the shoe bottom. 80
96. In a machine of the class described, means for operating on a shoe bottom, a shoe holder to which the shoe is presented right side up with its toe toward the operator, and means for clamping the shoe on the holder, said holder being movable about an axis extending transversely of the shoe to enable the shoe to be presented bottom up to the operating means. 85
97. In a machine of the class described, a heel breasting cutter, a shoe holder to which a shoe is presented with its top toward the operator, and means for clamping the shoe in the holder, said holder being arranged for inversion after the shoe is clamped to enable the shoe heel to be presented to the cutter. 90
98. In a machine of the class described, the combination of means for holding a shoe heel in predetermined position, a rotary tool arranged for bodily movement relatively to the heel, and means for moving the tool to treat the heel breast. 95
99. In a machine of the class described, the combination of means for holding a shoe heel in predetermined position, a rotary tool arranged for bodily movement relatively to the heel, and power operated means for moving the tool bodily to treat the heel breast. 100
100. In a machine of the class described, shoe supporting means, a rotary cutter constructed and arranged to form a concave face on the breast portion of the top lift of a heel, and means for moving the cutter bodily relatively to the heel to cause the cutter to do its work. 105
101. In a machine of the class described, the combination of means for holding a shoe heel in predetermined position, a rotary tool arranged for movement relatively to the heel, and automatic means for moving the tool bodily in predetermined relation to the heel to perform an operation thereon. 110
102. In a machine of the class described, the combination of shoe supporting means, a rotary cutter, a carrier for the cutter having an axis about which the cutter is movable in the longitudinal median plane of the shoe, and means for moving the cutter in said plane to form a concave surface on the heel. 115
103. In a machine of the class described, the combination of shoe supporting means, a rotary cutter having its axis located in the longitudinal median plane of the shoe, a support for the cutter movable about an axis extending transversely of the shoe, and means for moving the cutter about said transverse axis to cause the cutter to treat the heel breast. 120
104. In a machine of the class described, the combination of shoe positioning means, a rotary cutter having its axis directed substantially perpendicular to the shoe shank, and means for moving the cutter heightwise of the heel to cause it to engage the heel breast. 125
105. In a machine of the class described, the combination of shoe positioning means, and a rotary cutter movable laterally of and heightwise of the shoe heel to treat the heel breast. 130
106. In a machine of the class described, the combination of shoe positioning means, and a rotary cutter arranged for movement substantially heightwise of the heel in engagement with the heel breast. 135
107. In a machine of the class described, the combination of a shoe support, a rotary cutter mounted on a movable axis extending substantially heightwise of the heel of a shoe on the support, and means for moving the cutter to cause the cutter to operate on the heel breast. 140
108. In a machine of the class described, the combination of a shoe support, a rotary cutter mounted on a shaft extending heightwise of the heel and arranged for swinging movement, and means for swinging the cutter to cause it to act on the heel breast. 145
109. In a machine of the class described, the combination of a shoe support, a rotary cutter mounted on a shaft extending heightwise of the heel and arranged for swinging movement about an axis extending transversely of the shoe, and means for swinging the cutter shaft about said axis to cause the cutter to act on the heel breast. 150
110. In a machine of the class described, a shoe support, a rotary cutter mounted on a shaft extending heightwise of the heel of a shoe on the support, and means for moving

the cutter heightwise of the heel to cause the cutter to act on the heel breast.

111. In a machine of the class described, a shoe support, a rotary cutter mounted on a shaft extending heightwise of the heel of a shoe on the support and arranged for bodily movement transversely of the shoe, and means for moving the cutter shaft transversely and heightwise of the heel to treat the heel breast.

112. In a machine of the class described, the combination of means for holding a shoe and its attached heel in predetermined position, a rotary tool arranged for bodily movement relatively to the heel, and means for moving the tool to treat the heel.

113. In a machine of the class described, the combination of a shoe support, a rotary cutter mounted on a movable axis extending heightwise of the heel of a shoe on the support, and means for relatively moving the cutter and support to cause the cutter to operate on the heel breast in a direction heightwise of the heel.

114. In a machine of the class described, the combination of a shoe support, a rotary cutter arranged for bodily swinging movement, and means for swinging the cutter to cause it to act on the entire heel breast.

115. In a machine of the class described, the combination of a shoe support, a rotary cutter mounted on a shaft extending heightwise of the heel of a shoe on the support, and means for relatively moving the cutter and the support heightwise of the heel to cause the cutter to act on the heel breast.

116. In a machine of the class described, a shoe support, a rotary cutter mounted on a shaft and arranged for bodily movement laterally of the shoe, and means for moving the cutter laterally of the heel to cause the cutter to treat the heel breast.

117. In a machine for operating on heels, the combination of shoe and heel holding means, a rotary cutter having its axis extending in the direction of the height of the heel and located at one side of the shoe, means for moving the cutter to position its axis over the shoe, and means for moving the cutter substantially in the direction of its axis to cause it to treat the heel breast.

118. In a machine of the class described, the combination of an elongated rotary cutter having a curved end cutting portion and mounted for rotation about its longitudinal axis, a shoe support constructed and arranged to present the heel to the cutter with

the plane of its tread face substantially perpendicular to the axis of the cutter, means for relatively moving the support and cutter in a direction substantially parallel to the shoe shank, and means for relatively moving the support and cutter about an axis located at approximately the center of curvature of the cutter.

119. In a machine of the class described, the combination of a rotary cutter, and means for positioning a shoe with the heightwise center line of the heel breast and the cutter axis in the same plane, said positioning means and the cutter being arranged for relative movement about an axis perpendicular to the cutter axis to cause the heel breast to engage the cutter.

120. In a machine of the class described, the combination of a rotary cutter, and means for positioning a shoe with the heightwise center line of the heel breast and the cutter axis in the same plane, said positioning means being arranged for movement about an axis perpendicular to the cutter axis to cause the heel breast to engage the cutter.

121. In a machine of the class described, the combination of an egg-shaped cutter mounted for rotation on its longitudinal axis, means for positioning a heel, said cutter and positioning means being relatively movable to cause the cutter axis to lie in the longitudinal median plane of the heel, and means permitting relative movement of the positioning means and the cutter about an axis perpendicular to the cutter axis to cause the portion of the heel breast adjacent to its tread face to engage the cutter.

122. In a machine of the class described, the combination of an egg-shaped cutter mounted for rotation on its longitudinal axis, and means for positioning a heel so that the cutter axis lies in the longitudinal median plane of the heel, said positioning means being arranged for movement about an axis perpendicular to the cutter axis to cause the portion of the heel breast adjacent to its tread face to engage the cutter.

123. In a machine of the class described, the combination of a rotary cutter, and shoe locating means movable transversely of the cutter axis and also movable about an axis adjacent to the heel.

In testimony whereof I have signed my name to this specification.

ELMER B. GRUSH.
